UNITED STATES PATENT OFFICE.

EDWARD A. FARISH, OF ST. LOUIS, MISSOURI.

CHAIR.

SPECIFICATION forming part of Letters Patent No. 727,119, dated May 5, 1903.

Application filed June 14, 1902. Serial No. 111,654. (No model.)

To all whom it may concern:

Be it known that I, EDWARD A. FARISH, a citizen of the United States, residing at St. Louis, in the State of Missouri, have invented 5 a certain new and useful Improvement in Chairs, of which the following is a full, clear, and exact description, such as will enable others skilled in the art to which it appertains to make and use the same, reference being had 10 to the accompanying drawings, forming part of this specification, in which—

Figure 1 is a rear elevation of my improved chair. Fig. 2 is a sectional view on line 2-2, Fig. 1; and Fig. 3 is a fragmentary top plan 15 view of the chair-back, portions being shown in section to more clearly illustrate the coöperation of the several parts.

This invention relates to a new and useful improvement in chairs, the object being to 20 combine a chair and clothes-press into a single article of furniture in a simple and efficient manner and which can be cheaply manufactured.

With this object in view the invention consists 25 in the provision of a movable panel adapted to coöperate with a fixed panel to form a clothes-press, said panels also serving as the chair-back proper.

Other features of novelty will be hereinafter 30 more fully described, and set forth in the claim.

In the drawings, 1 indicates the chair-seat, 2 the front legs, and 3 the rear legs, said rear legs extending upwardly and forming 35 uprights or standards 4 for the chair-back. Fixedly mounted between the standards 4 is a panel 5, which serves to brace the chair-back and constitutes one member of the clothes-press, which I will now describe.

6 indicates a movable panel hinged at its lower end to the stationary panel 5 by hinges 7. These hinges are preferably made of 40 spring metal and adapted to yield slightly to accommodate the press to trousers (or other

articles of clothing) of varying thickness and 45 which will exert a pressure upon the articles to be pressed.

The movable panel is provided near its upper end with notched extensions 8, which are adapted to project through suitable openings 50 in the fixed panel and engage with a pivoted leaf-spring 9, mounted on the rear of said fixed panel, and whose tendency is to pull the two panels together to exert a pressing action. A suitable hook 10 may also be provided at 55 the rear of the chair, upon which a coat may be suspended either directly therefrom, or a suitable coat-hanger 11, as shown in dotted lines in Fig. 1, may be provided.

12 indicates a box arranged under the bottom of the chair for the reception of shoes, &c., access being had thereto through a suitable door 13.

I am aware that minor changes in the construction, combination, and arrangement of 65 the several parts may be made and substituted for those herein shown and described without in the least departing from the nature and principle of the invention.

Having thus described my invention, what 70 I claim, and desire to secure by Letters Patent, is—

In a chair, the combination with a chair-back consisting of a fixed panel, of a hinged panel supported therefrom, hinges for said 75 panel, catches projecting from said hinged panel adapted to pass beyond the fixed panel, and a flat spring pivotally supported on the exterior of the fixed panel and adapted to co-operate therewith to yieldingly lock said panels in position; substantially as described.

In testimony whereof I hereunto affix my signature, in the presence of two witnesses, this 9th day of June, 1902.

EDWARD A. FARISH.
